UNITED STATES PATENT OFFICE.

HOWARD J. KERR, OF BAYONNE, NEW JERSEY, ASSIGNOR TO THE BABCOCK & WILCOX COMPANY, OF BAYONNE, NEW JERSEY, A CORPORATION OF NEW JERSEY.

AIR-COOLED WALL.

Application filed June 12, 1919, Serial No. 303,671.

To all whom it may concern:

Be it known that I, HOWARD J. KERR, a citizen of the United States, residing at Bayonne, in the county of Hudson and State of New Jersey, have invented a new and useful Improvement in Air-Cooled Walls, of which the following is a specification.

My invention relates to an apparatus for ventilating a furnace wall and more particularly to such an apparatus in which the air for such ventilation is taken from the wind box or air distributing box of the stoker.

My invention will best be understood by reference to the accompanying drawings in which Figs. 1 to 8 show one general form of my invention, in which Fig. 1 is a vertical section through the furnace wall and a portion of the stoker embodying my invention; Fig. 2 is a vertical sectional elevation with a portion of the wind box broken away and taken through the wall 10 at the rear of the wind box in Fig. 1; Figs. 3, 4, 5 and 6 are sectional views on the lines 3—3, 4—4, 5—5 and 6—6, respectively, of Fig. 1; Fig. 7 is a sectional view similar to Fig. 1 taken through the furnace wall and showing a slightly modified form of my invention; Fig. 8 is a vertical sectional elevation, partially broken away, and taken through the wall 10^a at the rear of the wind box in Fig. 7; Figs. 9 to 16 illustrate modifications in which a ventilating box is disposed in the lower portion of the furnace wall, Fig. 35 9 being a vertical section through the lower portion of the wall; Fig. 10 an elevation of the structure shown in Fig. 9 as viewed from within the furnace; Fig. 11 a perspective view illustrating a section of one of the ventilating boxes with the associated parts; Fig. 12 is a vertical section similar to Fig. 9 and illustrating a modified form of my invention, in which a supplemental wall is used; Fig. 13 is an elevation of the structure shown in Fig. 12 viewed from within the furnace; Fig. 14 is a horizontal section on the line 14—14 of Fig. 12; Figs. 15 and 16 are detail views illustrating modifications of the construction for preventing the separation of the ventilating pipes from the supplemental wall, and Figs. 17 and 18 are sectional views illustrating modified forms of sectional ventilating boxes.

Referring, now, to the drawings, and first

to Figs. 1 to 8, in which I have illustrated the preferred form of my invention 10 is a furnace wall, here shown as a front furnace wall, and 11 is a stoker for the furnace, the stoker here being shown as an underfeed stoker, the wind box or air distributing box 12 of which is preferably disposed below the furnace wall 10, usually the front wall, and serves to carry a part of the weight of the front wall. Air under pressure is supplied to the wind box 12 in a well understood manner. The first seven rows of the brickwork of the wall are indicated by the reference numerals 13, 14, 15, 16, 17, 18 and 19, respectively. In the embodiment of my invention here shown, the first row 13 of 70 the brickwork is laid solid across the boiler except for openings through which pass the tubes 20 which are connected to the wind box 12 and by means of which the furnace wall is ventilated. The second 75 course 14 is preferably a header course, breaking joints with the first course and provided on the furnace side with narrow spaces 14^a between the adjacent bricks. The pipes 20, which are connected to the wind box 12, also pass through the bricks of the second course and extend nearly flush with the top of the same, the space surrounding the upper ends of the pipes being carefully grouted as at 21 so that the air passing 80 through the pipes may not pass down around the bottom of the wall. The third course 15 is provided with an air space 22, as best shown in Figs. 1 and 3, which extends the entire width of the boiler. The 85 bricks of this course on the furnace side are also spaced apart, as at 15^a, the fourth, fifth and sixth courses also being spaced apart in a similar manner, as indicated at 90 16^a, 17^a and 18^a, respectively. The fourth course 16 is built up similarly to the third course, with the exception that every third brick 23 is a tying brick across the air space 22. The fifth course is similar to the fourth 95 course, with the exception that the tying brick 24 is located between the tying bricks of the fourth course. The sixth course 18 covers up the air space 22 of the fifth course. The seventh course is a stretcher course, as indicated; i. e., the bricks are laid with 100 their long faces to the furnace. The eighth course 19 is a header course, the ties 25 being located in the spaces 19^a between the adjacent bricks.

With the described arrangement, the air passes from the wind box of the stoker into

the air space 22 formed within the third, fourth and fifth courses, and passes through the spaces formed between the bricks on the furnace side of these courses to the furnace, 5 as well as through the spaces between the bricks of the second and sixth courses to the furnace.

In Figures 7 and 8 I have shown a slightly modified form of my invention, in which 10 like parts are indicated by the same reference characters used in connection with Figs. 1 to 6, but with the exponent "a" added, and in which the ventilating passages, which I have indicated by the reference 15 numeral 15^b, are confined to one of the courses, here shown as the third course, and extending from the point where the pipes 20^a from the wind box enter this course to the interior of the furnace, as indicated in 20 Figure 8. The upper ends of the pipes 20^a are here shown as bent rearwardly to direct the air to the various passages.

Referring now to Figs. 9 to 11, 10^b is a furnace wall supported, in whole or in 25 part, on the wind box or air distributing box 12^b, a ventilating box 27 being disposed in the lower portion of the wall and offset from the wind box 12^b, as best shown in Fig. 9. The ventilating box 27 is preferably 30 formed in sections, and in the form here shown, the various sections are closed at their ends, and are slightly spaced apart. By thus making the ventilating box in sections, there is a less tendency to warp out of 35 shape and distort the wall. The back of the ventilating box may be formed of plates 27^b, which are secured against the outer surface of the wall, as indicated. The ventilating box 27 communicates with the wind box or air distributing box 12^b by means of 40 tubes 28. The lower portion of the wall 10^b is provided with openings 29 into which project pipes 30 which communicate with the 45 ventilating box 27.

Fig. 17 illustrates a ventilating box 27^c similar in cross section to that of Fig. 9 but in which the ends are not closed, the walls of the adjacent sections abutting against each other as at 27^d, so as to provide a continuous passage through the sections. Fig. 18 illustrates a further modification in which the ends of the sections 27^e are closed similarly to those shown in Figs. 9 to 11, but in which communication 55 between the sections is furnished by means of pipes 43 engaging openings in the ends of the sections forming a sliding fit with one of the sections, as at 44, to provide for free expansion of the various sections.

In Figs. 12 to 16 I illustrate my invention 60 in conjunction with a furnace wall, which I have indicated in general by the reference character 10^d, and which comprises a main wall 10^d and a supplemental wall 10^e, which 65 protects the lower portion of the main wall.

The supplemental wall is supported, in whole or in part, on the wind box 12^e of the stoker 11^e, while the main wall is supported on the ventilating box 31. The sides of the ventilating box may be formed of 70 channel irons 32, the flanges of which project inwardly, as indicated, the ends of the boxes being closed by flanged plates 33 (see Fig. 14). The ventilating boxes may be secured at their ends to columns 34 or, 75 if the boxes are made in sections in accordance with the practice outlined in Figs. 9 to 11, they may be supported on a number of struts.

In order to cool the supplemental wall 80 10^e and the lower portion of the main wall 10^d, the supplemental wall is provided with openings 35 into which project pipes 36 connected to the ventilating box 31, the 85 passages in the wall thus furnishing communication between the ventilating box and the interior of the furnace chamber. Similarly, the lower portion of the main wall 10^d is provided with openings 37, L-shaped in form, into which project 90 pipes 38, as best shown in Fig. 12, the pipes being connected to the ventilating boxes 31. The ventilating box in this case is connected by a pipe 39 to the air chamber 40 of the stoker. The said pipe preferably 95 lies wholly within the setting, as indicated in Fig. 14.

In order to tie or bind the supplemental wall to the ventilating box, and hence to the main wall, the ends of the pipes 36 are 100 provided with flanges 41, which engage corresponding notches 42 formed in the walls surrounding the opening 35, the notches preferably being sufficiently wide to provide a limited amount of movement between 105 the ventilating box and wall and thereby provide for expansion and contraction. In the construction shown in Fig. 14 the ends of the pipes are split and bent outwardly, while in Fig. 15 a flange 41^a is formed integral with the end of the pipe 36, and engages a notch 42^a in the wall. In the construction shown in Fig. 16 the flange 41^b 110 is formed on a sleeve or thimble, which is secured at the end of the pipe, the flange 115 engaging a notch 42^b formed in the wall.

The pipes 36 and 38 are surrounded by grouting or other material, as indicated in Fig. 12.

It will be apparent that my invention 120 provides a simple and efficient means for ventilating the furnace wall, and one in which the cutting up of the brick work is reduced to a minimum.

What I claim and desire to secure by 125 Letters Patent of the United States is:

1. In combination with a furnace wall formed with a ventilating passage, a stoker having a wind box which serves as a support for said wall, means for introducing air 130

from said wind box to said passage, and means for ventilating said wall by the air from said ventilating passage.

5 2. In combination with a front furnace wall formed with a ventilating passage, a stoker, a wind box forming part of the stoker structure and serving as a support for said wall, means for introducing air from said wind box to said passage, and
10 means for ventilating said wall by the air from said ventilating passage.

15 3. In combination with a furnace wall formed with a ventilating passage, a stoker, a wind box forming part of the stoker structure and serving as a support for said wall, and a plurality of pipes furnishing communication between said wind box and said passage.

20 4. In combination, a furnace wall formed with passageways leading to the furnace chamber, a stoker having a wind box serving as a support for said wall, and connections for conducting the air upward from said wind box through the lower courses of said
25 wall to said passageways.

30 5. In combination, a furnace wall formed with an air space, a stoker having a wind box serving as a support for said wall, and connections for supplying air from said wind box to said space through the bottom of said wall, said wall being provided with passages leading from said space to the inner face of said wall.

35 6. In combination, a furnace wall formed with an air space extending longitudinally of said wall, a stoker having a wind box serving as a support for said wall, and connections for supplying air from said wind box to said space, said wall being provided
40 with passages leading from said space to the inner face of said wall.

45 7. In combination, a furnace wall formed with an air space, the bricks on the inner side of said wall opposite said space being spaced to provide passages leading from said space to the inner face of the wall, a stoker having a wind box serving as a sup-

port for said wall, and connections for supplying air from said wind box to said air space.

50 8. In combination, a furnace wall formed with an air space extending across a plurality of courses of bricks, tying bricks intermediate the height of said space and extending across the space, a stoker having a wind box serving as a support for said wall, and connections for supplying air from said wind box to said space, said wall being provided with passages leading from said space to the inner face of said wall.

55 9. In combination, a furnace wall having an air space extending longitudinally thereof, a stoker having a wind box located beneath and serving as a support for said wall, and connections arranged at various points along said wind box for supplying air to said air space, said wall being provided with passages leading from said air space to the inner face of the wall.

60 10. In combination, a furnace wall having an air space extending longitudinally thereof, a stoker having a wind box located beneath and serving as a support for said wall, and connections arranged at various points along said wind box for supplying air to said air space, the bricks of said wall at the rear of said air space being spaced apart to form passages leading from said air space to the face of said wall.

65 11. In combination with a furnace wall provided with a ventilating passage, a stoker having a wind-box which serves as a support for said wall, means for introducing air from said wind-box to said passage through the bottom of said wall, and means for ventilating said wall by the air from said ventilating passage.

70 In testimony whereof, I have hereunto signed my name in the presence of two subscribing witnesses.

HOWARD J. KERR.
